(57) **CLAIM**

The ornamental design for a coffee machine dripper, as shown and described.

DESCRIPTION

FIG. 1 is a front, right side, perspective view of a coffee machine dripper showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an environmental perspective view thereof;

FIG. 9 is an environmental perspective view thereof where the bottom portion of the coffee machine dripper is removed for ease of illustration; and,

FIG. 10 is an environmental perspective view thereof where the top portion of the coffee machine dripper is removed for ease of illustration.

The broken lines show environment of the coffee machine dripper that forms no part of the claimed design.

1 Claim, 10 Drawing Sheets
